ELECTRODE STRUCTURE OF ELECTROLYTIC CONDENSERS

Julius Edgar Lilienfeld, Winchester, Mass., assignor to Ergon Research Laboratories, Inc., Malden, Mass., a corporation of Delaware

Application October 31, 1931, Serial No. 572,297

10 Claims. (Cl. 175—315)

The invention relates to electrolytic condensers, and more particularly to a novel construction and operation thereof. The invention is particularly adaptable to electrolytic condensers of the A. C. type and utilizing a single container for the electrolyte, said container with electrolyte then constituting the cathodic electrode and retaining two systems of filmed electrodes of alternately disposed elements of opposite polarity, which are mounted therein for connection to a source of alternating current.

In arrangements of this type, the different elements constituting the filmed electrodes are located with their surfaces lying closely together so that the capacity current goes through the electrolyte directly from one layer to the next. However, certain portions, more especially the supporting riser members or rods for the electrodes, present outer surfaces which face the inside wall of the container. This creates a condition whereby the capacity current going to the outside surface of each layer of the electrodes travels from the non-formed inside wall of the cathodic container to the formed outside surface of the riser or rod.

It is particularly desirable, especially for commercial reasons, to construct these containers of aluminum, and it has been observed that the hereinbefore described condition results in the disintegration of the aluminum metal surface facing the risers such that relatively large particles of aluminum are loosened from the container wall, drop or are torn off, and collect on the bottom. This destructive action will eventually perforate the wall of the container, and it is an object of the present invention to make provision for preventing such destructive action thereon.

This may readily be effected by introducing intermediate and active electrode members of suitable metal between such parts of the elements of the two systems of filmed electrodes as do not face each other across the narrow spacing, but rather face the container. For example, copper strips may be secured to the supporting structure in such a manner as to partly surround the risers or supporting rods for the electrodes, the same being located between such risers and the container wall and in close proximity to the former.

In the provision of these metallic active electrodes, I have found, furthermore, that not only is the deterioration of the container wall obviated, but an important effect may be had upon the electrolyte itself. I have discovered that the electrolyte utilized for electrolytic condensers may be constituted as entirely free of any alkaline com-

ponents, such as result from the usual addition of borax or like alkali salts to electrolytes of this nature. Thus, it is possible to use a nearly saturated solution of boric acid, salicylic acid, etc., in water, if the same be also saturated with electro- 60 positive ions such as may be obtained from metals as copper, nickel, chromium, cadmium, cobalt, zinc, etc. Or, alcoholic solutions of such weak acids, as well as a mixture of water and alcohols, may be utilized and saturated with metallic ions. 65

These ions may readily be introduced into the electrolyte, for example, by immersing two of the metal electrodes therein and causing a current to flow therebetween until the electrolyte becomes saturated with the electropositive ions. Such 70 saturation has the purpose merely of reducing the high resistance of electrolytes of this nature, and in the case of a pure aqueous boric acid solution utilized for the electrolyte, copper ions have been found very effective. 75

In this connection it is desirable to have some active copper surfaces permanently located in the novel electrolyte for maintaining its saturation with copper ions and the provision of the intermediate active electrodes in the condenser construction hereinbefore described serves also for the purpose of maintaining this ion concentration. 80

Other metal ions such as nickel, chromium, cadmium, cobalt, zinc, etc., may be utilized, but 85 copper ions from the intermediate active electrode afford a relatively inexpensive and highly satisfactory means for attaining the desired results.

In the use of an extremely high resistance electrolyte for an electrolytic condenser, it becomes necessary to space the electrode elements relatively closely; and by utilizing an electrolyte substantially free from alkaline components, there is a relatively low electric leak therebetween, 90 the condenser possesses a higher breakdown voltage, requires a lower biasing voltage, and the power loss in the dielectric layer is particularly low. A further reduction in power loss results through the addition of the metallic (copper) 95 ions inasmuch as the resistance of the electrolyte is thereby appreciably diminished. The said dielectric layer, furthermore, is more stable in that it retains its organized condition better during the idling periods, thus reducing the electric leak 100 after such periods. 105

The accompanying drawing illustrates one embodiment of an electrolytic A. C. condenser to which the novel provisions aforesaid are particularly applicable, and in the drawing Fig. 1 110

is a vertical section through an A. C. condenser provided with intermediate active electrodes; and Fig. 2 is a horizontal section thereof, taken on the line 2—2, Fig. 1.

5 Fig. 3 is a front elevation, and Fig. 4 an underneath view of an active intermediate electrode as utilized in the novel combination.

Referring to the drawing, 10 designates a container which is of aluminum and is designed to 10 retain a suitable electrolyte 11 and the novel electrode structure. The electrolyte is, preferably, free from alkaline components, for example, it may consist of an aqueous solution of boric acid or of salicylic acid, or of alcoholic solutions 15 thereof. To reduce the resistance of said electrolyte, the same is saturated with electropositive (metallic) ions, for example, those of copper as in temporarily passing an electric current between two copper electrodes (not shown) dipping therein and as is well understood, or by 20 adding thereto a suitable salt such as copper borate.

25 Into the electrolyte is designed to dip, for example in the case of alternating current operation, a plurality of systems of electrodes comprising the respective formed aluminum plates 12 and 13 of opposite polarity and shown in the present instance of frusto-conical shape substantially as set forth in my copending application 30 Serial No. 531,901. These plates may be mounted, similarly to the arrangement shown in the aforesaid application, upon two sets of risers 15 and 16 which are equidistantly spaced around the vertical axis of the respective electrode elements. One of each set of risers, also, has an upper portion 17 and 18, respectively, projecting beyond the cover member 19 of the condenser and affording the terminal leads 20 and 21, by which connection may be had to a suitable source 35 of alternating current, the electrolyte of the condenser being biased to a predetermined negative voltage, for example, as is set forth in my copending application Serial No. 462,252. Provision is also made for mounting above and below the two sets of filmed elements top and bottom shielding elements 22 and 23 of copper, as on risers 24 which are thus electrically connected to the said cover member through the said risers 24.

40 The two sets of risers 15 and 16 are arranged to be supported at the bottom ends by the bottom plate 26 and are insulated therefrom by the respective recessed insulating bushings 27 and 28, respectively, substantially in the manner set forth in my said application, Serial No. 531,901, and the same also pass through an upper plate 29 carried by the risers 24.

45 In accordance with the invention, the exposed outer surfaces of the risers 15 and 16, which 50 constitute active electrode surfaces not facing one of opposite polarity across a narrow spacing, but rather the inner wall of the container 10, are arranged to be surrounded over the said exposed portions by further metallic electrodes located in proximity to said surfaces and 55 intermediate the same and the inner wall of the container. For example, thin strips 30 of a metal such as copper, nickel, chromium, cadmium, cobalt, zinc, etc., and preferably the first-named, 60 are rigidly secured at their opposite ends through 65 end flanges 31 and 32 to the said bottom and top plates 26 and 29.

70 In the provision of these active intermediate electrodes the capacity current may go directly from the strips to the risers and not from the

non-formed inside wall of the container to the formed outer surface of a riser. Disintegration of the inner wall of the container is thus obviated, and the life of the condenser greatly prolonged.

Also, the benefits resulting from the use of narrowly spaced electrodes and a relatively high resistance electrolyte may thus be retained. Furthermore, these metallic shielding or active intermediate electrode members serve to maintain the concentration of metallic ions in the electrolyte and, of course, should be of the same metal as the ions contained in the electrolyte.

I claim:

1. The combination with an A. C. electrolytic 90 condenser embodying a cathodic metallic container for electrolyte and coacting electrodes mounted therein, and comprising a plurality of formed elements narrowly spaced apart; of shielding cathodic electrodes of non-filming metal 95 insulated from the formed elements and located between the inner wall of the container and such parts of the electrode elements as are unexposed to a coacting element.

2. The combination with an A. C. electrolytic 100 condenser embodying a cathodic aluminum container for electrolyte and coacting electrodes mounted therein, and comprising a plurality of formed elements narrowly spaced apart; of shielding cathodic electrodes of non-filming 105 metal insulated from the formed elements and located between the inner wall of the container and such parts of the electrode elements as are unexposed to a coacting element.

3. The combination with an A. C. electrolytic 110 condenser embodying a cathodic metallic container for electrolyte and coacting electrodes mounted therein, and comprising a plurality of formed elements narrowly spaced apart; of shielding cathodic electrodes of copper insulated 115 from the formed elements and located between the inner wall of the container and such parts of the electrode elements as are unexposed to a coacting element.

4. The combination with an A. C. electrolytic 120 condenser embodying a cathodic metallic container for electrolyte and coacting electrodes mounted therein and constituted by alternately disposed formed plates narrowly spaced apart, and supporting risers for interconnecting alternate plates; of shielding cathodic electrodes of non-filming metal insulated from the formed plates and located between the inner wall of the container and the outer surfaces of said risers which are unexposed to a coacting element. 125

5. The combination with an A. C. electrolytic condenser embodying a cathodic metallic container for electrolyte and coacting electrodes constituted by alternately disposed formed plates, supporting risers for interconnecting alternate 135 plates, and top and bottom cathodic plates associated with the risers and insulated therefrom; of metal strips secured at their opposite ends to the respective plates and about the surface of the risers facing the inner wall of the container and 140 narrowly spaced from said risers.

6. The combination with an A. C. electrolytic condenser embodying a cathodic metallic container for electrolyte and coacting electrodes constituted by alternately disposed formed plates, 145 supporting risers for interconnecting alternate plates, and top and bottom cathodic plates associated with the risers and insulated therefrom; of strips of copper having top and bottom flanges rigidly secured at their opposite ends to the re- 150

spective plates and extending about the surface of the risers facing the inner wall of the container and narrowly spaced from said risers.

7. An A. C. electrolytic condenser, comprising

5 a cathodic metallic container for an electrolyte, an electrolyte embodying a free weak acid of the group consisting of boric acid, salicylic acid and alcoholic solutions thereof and free from alkaline components, said electrolyte containing also elec-
10 tropositive ions other than alkaline ions, a plurality of filmed electrodes dipping into said electrolyte, and non-filming cathodic metal elements associated with said filmed electrodes for shielding the container and for maintaining the con-
15 centration of the electropositive ions of said electrolyte.

8. An A. C. electrolytic condenser, comprising a cathodic metal container for an electrolyte, an electrolyte embodying a free weak acid of the group consisting of boric acid, salicylic acid and alcoholic solutions thereof free from alkaline components, said electrolyte also containing copper ions, a plurality of filmed electrodes dipping into said electrolyte, and means associated with 20 the said filmed electrodes for shielding the container and for maintaining the concentration of the copper ions in the electrolyte.

9. An A. C. electrolytic condenser, comprising

a cathodic metal container for an electrolyte, an electrolyte embodying a free weak acid of the group consisting of boric acid, salicylic acid and alcoholic solutions thereof free from alkaline components, said electrolyte also containing copper ions, a plurality of filmed electrodes dipping into said electrolyte, and strips of copper dipping into the electrolyte for maintaining the concentration of the copper ions therein and located between the inner wall of the container and such parts of the filmed electrodes as are unexposed to a coacting electrode.

10. The combination with an A. C. electrolytic condenser, embodying a cathodic aluminum container for an electrolyte, an electrolyte of the group consisting of boric acid, salicylic acid and alcoholic solutions free from alkaline components, said electrolyte containing also copper ions, and coacting electrodes mounted therein and comprising a plurality of formed elements narrowly spaced apart; of strips of copper located between the inner wall of the container and such parts of the electrode elements as are unexposed to a coacting element, the said strips constituting shielding cathodic electrodes and serving also to maintain the concentration of the copper ions in the electrolyte.
